UNITED STATES PATENT OFFICE.

JOSEPH S. DUNCAN, OF CHICAGO, ILLINOIS.

ADDRESSING-MACHINE.

1,075,840.

Specification of Letters Patent.

Patented Oct. 14, 1913.

Application filed March 24, 1911. Serial No. 616,750.

To all whom it may concern:

Be it known that I, JOSEPH S. DUNCAN, a citizen of the United States, residing at Chicago, in the county of Cook and State of Illinois, have invented new and useful Improvements in Addressing-Machines, of which the following is a specification.

This invention relates to addressing machines and it has for its object to print from a part of the printing form, or the whole form, and to provide means for automatically operating the machine in this manner.

In the usual operation of addressing machines one complete impression is taken from each printing form at each operation of the machine. Sometimes the machine is adjusted so that several complete impressions may be taken from each printing form, but as far as I am aware an impression from the whole form has always been taken at each operation of the machine.

I have found it desirable to provide for taking impressions from parts of the printing form as well as from the whole form, for certain purposes. For example, some printing devices embody with an address form a certain additional form bearing other information and it is desirable to print the address only on an envelop and the complete form on a bill to be inclosed in the envelop. Again, addressing machines are largely used for addressing gas bills and the like which embody stubs to be retained by the gas company when the bill is received. It is sufficient in many instances to omit an end portion of the address as printed upon the stub. By so doing the size of the stub may be materially decreased and a considerable saving in cost of paper effected. Again, it is sometimes desirable to print the name only on papers to be inclosed in an envelop which, of course, must receive the complete address. Many other instances might be referred to to show the advantages and uses of my present invention but the foregoing will be sufficient for the purposes of this application.

With these ends in view the invention has for its object to provide means of simple character whereby an addressing machine will automatically operate to print the whole or part of a form in successive operations of the machine.

To illustrate my invention I have shown it in the accompanying drawings embodied

in an addressing machine of the general type shown in my Patent No. 803,677 dated November 7, 1905 but it will be understood of course that this is for purposes of illustration only and not with the intention of limiting the scope of the invention to that particular type of machine as it will be observed, when the invention is understood, that it is capable of embodiment in addressing machines which differ to a more or less extent from the one shown.

Referring to the drawings, which illustrate only so much of the machine as is necessary to understand the invention, Figure 1 is a top plan view, partly in section, of a portion of an addressing machine showing my invention embodied therewith. Fig. 2 is a side elevation, partly in section. Fig. 3 is a bottom plan view of the work table with the associated parts of my invention. Fig. 4 is a detail sectional view on the line 4-4 of Fig. 1 with the platen removed showing the parts in normal position at rest and Fig. 5 is a similar view showing the parts in printing position. Fig. 6 is a detail front elevation, partly in section, of the platen head. Fig. 7 is a detail sectional view showing the platen and the cam operating rod. Fig. 8 is a detail sectional view on the line 8-8 of Fig. 6. Fig. 9 is a view, partly in section, illustrating the tripper mechanism for operating the sectional platen. Fig. 10 is a front elevation and Fig. 11 is a side elevation of a platen head and platen showing another form of my invention. Fig. 12 is a detail plan view on the line 12-12 of Fig. 10. Fig. 13 is a transverse sectional view on the line 13-13 of Fig. 10 showing one section of the platen in printing position, and Fig. 14 is a similar view showing the other section of the platen in printing position. Fig. 15 is a perspective view of one section of the platen illustrated in Figs. 10 to 14. Fig. 16 is a detail view showing the anti-smudge devices for use with the form of the invention illustrated in Figs. 10 to 15.

In the drawings, 1 is the frame of the machine, 2 the carrier for moving the printing devices 3 one at a time to printing position, 4 is the work table which is mounted on the frame, 5 is the platen arm pivotally mounted at 7 on the frame and carrying the platen head 6. The envelops, bills or other things to be printed are placed

one at a time upon the work table against an adjustable gage 8 thereon, the printing devices are moved from a supply to printing position beneath an opening 9 in the work table, and the platen arm is swung to carry the platen into engagement with the envelop 10 and press it against the printing form through the opening 9 at each operation of the machine (Figs. 4, 5).

10 Heretofore the platen for an addressing machine has been made to print from the entire form at each operation but my invention contemplates a platen, which can be used as before to print from the whole form, 15 but composed of separately operable sections which make it possible to print from parts of the form instead of the whole form.

In Figs. 6-8 I have shown one type of 20 sectional platen embodying my invention and referring thereto 11 is the platen adjustably mounted on the head 6 and 12 and 13 are the two sections of the platen each of which has a facing 14 of suitable character. The section 12 is fastened rigidly to the base 11 and the section 13 is pivotally mounted at one end 15 in a recess 16 in the relatively fixed section 12. A spring 17 normally holds the movable section out of 25 operative position. A rod 18 is mounted to rock in the platen section 12 and it has a cam face 19 to engage the back of the movable section 13 and push it outward against the tension of spring 17 and into operative 30 position. The means for operating the rod 18 comprise a crank arm 20 rigidly mounted on one end thereof and a pull-bar 21 pivotally mounted at one end to the free end 22 of the crank (Fig. 2). This pull-bar 35 is arranged to slide on a fixed pin 23 in the bracket 24 mounted on the work table and it is held in engagement with the pin by a spring 25 attached to the bar and to the rod 18 (Figs. 2, 6). In the normal 40 operation of the machine the projection 26 on the pull-bar would engage the pin 23 and thereby stop the sliding movement of the pull-bar and cause the rod 18 to rock and force the movable section 13 of the 45 platen into operative position at each operation of the machine, but means are provided to control this movement of the pull-bar as hereinafter described.

A cam device 27 is rotatably mounted on 50 the bracket 24 and it is provided on its upper face with a plurality of projections 28 (Figs. 1, 2). A feed bar 29 is pivotally mounted at 30 on the platen arm and is arranged to engage the projections 28. On 55 the downward movement of the platen the feed bar is carried forward and its forward end slides over and engages one of the projections. On the upward movement of the platen the feed bar is pulled backward 60 and the cam device is turned a step. The

feed bar may be thrown upward out of operative relation to the cam device and held in this position by a pivoted locking device 31 which can be thrown over to engage the shoulders 32 on the feed bar (Fig. 2). A lever 33 is pivotally mounted at 34 on the bracket 24 and one end of this lever carries a roller 35 which travels in engagement with a cam 36 on the cam device 27 (Fig. 3). The other end of lever 33 is connected by a link 33' with a rod 37 which operates a plate 38 beneath the work table (Figs. 1, 3). The platen 38 is suitably guided in its movement and for this purpose is preferably shaped at 39 to slide 40 on a raised bed 40 on the work table, besides having a slot 41 to engage the holding screw 42. The plate 38 is adapted to be projected beneath the opening 9 in the work table to lie between that portion of the work and the printing device below the movable section of the platen during the printing operation to prevent any possibility of the work engaging that part of the printing device which is not to be printed. This plate 45 also protects the work from smudging. The cam may be variously made and timed to operate the cover and anti-smudge plate 38 at each operation of the machine or at alternate operations or otherwise, as desired.

A tripper device 43 is pivotally mounted on the bracket 24 (Fig. 9) and a spring 44 attached to said device holds it in contact with an arm 45 fast on lever 33. In Fig. 3 the cam has two deep depressions 46 and 47 to receive the roller 35. When the roller lies in the deep depressions the plate 38 will be retracted, as shown in Fig. 3, and the tripper will be engaged by the arm 45 as shown in Fig. 9, so that the pull-bar can bring the movable section of the platen into operative position when the platen arm is operated. The entire platen will then engage the work and the whole form will print. When the cam device is turned to cause the roller 35 to engage one of the rest depressions therein the plate 38 will be projected forward and the lever 33 will swing in a direction away from the tripper 48 and spring 44 will pull the tripper along 50 with the lever until the pin 48 thereon engages and lifts the pull-bar 21 out of operative relation to pin 23 and thereby prevents it from operating the movable section of the platen which will remain in elevated 55 position (Figs. 6, 7). Only the fixed section 12 of the platen will then engage the work and only that part of the form beneath said section will print. The roller 35 is held in engagement with the cam by a spring 35' 60 (Fig. 1) attached to the lever 33 and to the bracket 24.

The cam device controls the operation of the movable section of the platen and also of the cover and anti-smudge plate. The

form of cam device shown in Fig. 3 provides for one complete and two part impressions from each of two printing forms, or one complete and one part impression from each of three printing forms, in each complete revolution of the cam device. The printing device carrier will be suitably operated to hold the printing device in printing position as long as may be necessary but the means for so doing form no part of the present invention. By changing the cam device the impressions may be varied, and by throwing out the feed lever 29 the machine may be operated to print the entire form at each operation.

The construction thus described provides for cutting out of operation one end of the form, whether such cut-out part is complete in itself or only a portion of an address. I also provide for cutting out one or more complete lines of a form in a similar manner and this embodiment of my invention is illustrated in Figs. 10-16. The platen comprises two longitudinal sections 50, 51 independently mounted to swing on two rods 52, 53 having cam faces 54, 55 to engage the sections. The section 50 is mounted on rod 52 and the section 51 is mounted on the rod 53. Springs 56 are interposed between the sections to separate them and to assist the cam rods in aiding the sections. Crank arms 57, 58 are mounted on the ends of the cam rods and these arms are pivotally connected to a pull-bar 59 which is operated as before described. The cover and anti-smudge plate 60 (Fig. 16) is made to cover that part of the form beneath the section 50 or that part beneath the section 51 and it is operated by lever 61 and cam 62, the latter being operated as heretofore described.

When the roller 63 lies in the deep depressions 64 of the cam the plate 60 will rest beneath section 50, and when the roller lies in the shallow depressions 65 the plate will rest beneath section 51. With this form of cam the sections of the platen will be brought alternately into operative position and the plate 60 will be moved alternately forward and backward accordingly.

The invention is simple in construction and automatic in operation. By changing the cams a great variety of work may be done. Various other changes in the construction and arrangement of parts may be made to adapt the invention to different machines and for different purposes without departing from the scope of the following claims.

What I claim and desire to secure by Letters Patent is:

1. In an addressing machine, the combination of a platen comprising a fixed section and a movable section, said movable section being pivotally mounted on the fixed section 85 to move toward and from the plane of the

operating face of said fixed section, and means for actuating said movable section.

2. A platen for an addressing machine, comprising a platen head, and a plurality of platen sections carried thereby for effecting 70 an impression from a printing form, one of said sections being fixed and another being pivotally mounted thereon to move toward and from the printing face of said fixed section.

3. In an addressing machine, the combination of a platen comprising a plurality of sections for effecting an impression from a printing form, one of said sections being pivotally mounted on an adjacent section 75 and means for automatically moving said pivotal section into the plane of said adjacent section at predetermined intervals.

4. A sectional platen for an addressing machine comprising a relatively fixed section, a relatively movable section, yielding means for normally returning said movable section in an inoperative position, and means for positively moving said section into operative position against the force of said yielding means.

5. A platen for an addressing machine comprising a fixed section, a relatively movable section pivotally mounted on said fixed section and yieldingly sustained in inoperative position, and means for automatically moving said movable section into operative position.

6. A sectional platen for an addressing machine comprising a relatively fixed section having a recess, a relatively movable section pivotally mounted in said recess and normally disposed in inoperative position, and means for positively moving said section into operative position against the force of said yielding sustaining force.

7. A platen for an addressing machine, comprising a fixed section having a recess, a relatively movable section pivotally mounted and yieldingly sustained in inoperative position in said recess, and means for automatically moving said movable section into operative position.

8. A platen for an addressing machine comprising a section having a recess at one 115 end and a relatively movable section arranged in said recess and pivotally engaged at one end with the recessed section and yieldingly connected at its other end therewith.

9. In an addressing machine, the combination of a platen comprising a fixed section, a movable section, a rotatably mounted cam for moving the movable section into operative position, means for automatically 125 operating said cam at predetermined intervals and means for automatically returning said movable section in inoperative position.

10. In an addressing machine, the combination of a sectional platen for effecting an 130

- impression from a printing form, one section of said platen being normally inoperative, and means for automatically moving said section into operative position as the 5 platen approaches printing position.
11. In an addressing machine, the combination of a sectional platen adapted to press the work against a printing form, means for holding a section of said platen out of operative position, and means adapted to be positioned between the platen and the form to prevent that part of the form opposite the inoperative section of the platen from printing. 10
12. In an addressing machine, the combination of a sectional platen adapted to engage and press the work against a printing form, means for throwing one of said sections out of operation and means for preventing accidental printing by the thrown out section. 15
13. In an addressing machine, the combination of a sectional platen for effecting an impression from a printing form, an oscillating arm carrying the platen, and means intermediate of the arm and one of the sections of the platen for moving said section as the arm oscillates. 20
14. In an addressing machine, the combination of a platen for effecting an impression from a printing form and comprising a movable section normally sustained out of operative position relatively to the remainder of the platen, and means operated by 25 movement of the platen for throwing said section into operative position.
15. In an addressing machine, the combination of a platen for effecting an impression from a printing form and comprising a movable section normally sustained out of operative position, means for throwing said section into operative position, and a tripoper for throwing out said throw-in means. 30
16. In an addressing machine, the combination of a platen for effecting an impression from a printing form and comprising a movable section normally sustained out of operative position, a cam rod operatively engaged with said movable section, a movable 35 arm carrying the platen, and means operated by said arm for operating said cam rod.
17. In an addressing machine, the combination of a platen for effecting an impression from a printing form, a plate, normally 40 disposed outside the path of travel of the platen, means for interposing said plate between the platen and a part of said form to prevent that part of the form covered by the plate from engaging the work interposed 45 between the form and the platen and mecha-
- nism for automatically actuating said means at predetermined intervals. 50
18. In an addressing machine, the combination of a sectional platen for effecting an impression from a printing form, a plate, 55 and means for interposing said plate between one of the sections of the platen and the form, substantially as and for the purpose specified. 60
19. In an addressing machine, the combination of a platen for effecting an impression from a printing form, a plate, a lever operatively connected to said plate, a cam for operating said lever, a movable arm carrying the platen, and means operated by 65 said arm for actuating said cam. 70
20. In an addressing machine, the combination of a platen comprising a movable section, a plate adapted to be projected over that part of the form opposite the movable 80 section, and means for moving said section and plate to operate conjointly. 85
21. In an addressing machine, the combination of a sectional platen, means for retaining one of said sections in inoperative position, a cam mounted on said platen, and means for operating said cam upon downward movement of the platen to cause said section to be moved into operative position. 90
22. In an addressing machine, the combination of a platen arm, a sectional platen mounted thereon, means for normally retaining one of said sections in inoperative position, a fixed abutment, and mechanism adapted to be brought into operative relation with said abutment upon downward movement of the platen whereby the normally inoperative platen section is moved into operative position. 95
23. In an addressing machine, the combination of a sectional platen, mechanism for moving one of said sections into operative position upon movement of the platen into printing position, and means for automatically rendering said mechanism inoperative 100 at predetermined intervals. 105
24. In an addressing machine, the combination of a sectional platen, mechanism for moving one of said sections into operative position upon printing movement of the platen, a plate adapted to be interposed between the platen and the printing form, and means for automatically interposing said plate and rendering said mechanism inoperative at predetermined intervals. 110
